UNITED STATES PATENT OFFICE.

JAMES DALTON, OF LOS ANGELES, CALIFORNIA.

DESIGN FOR A REEL-OVEN.

52,842.

Specification for Design.

Patented Jan. 7, 1919.

Application filed August 3, 1918. Serial No. 248,231. Term of patent 7 years.

To all whom it may concern:

Be it known that I, JAMES DALTON, a citizen of the United States, residing at Los Angeles, in the county of Los Angeles and State of California, have invented a new, original, and ornamental Design for a Reel-Oven, of which the following is a specification, reference being had to the accompanying drawing, forming part thereof.

The drawing is a perspective view showing the oven as viewed from the driving end thereof.

I claim:

The ornamental design for a reel oven, as shown.

JAMES DALTON.

Witness:

LOUIS W. GRATZ.
